UNITED STATES PATENT OFFICE.

FRANK FLYNN, OF NEWARK, NEW JERSEY.

MOLD FOR CONCRETE STRUCTURES.

Application filed April 20, 1921. Serial No. 463,024.

To all whom it may concern:

Be it known that I, FRANK FLYNN, citizen of the United States, residing at Newark, in the county of Essex and State of New Jersey, have invented certain new and useful Improvements in Molds for Concrete Structures, of which the following is a specification, reference being had to the accompanying drawings.

10 The present invention has for its purpose the provision of a mold for constructing concrete, cement or other plastic structures of a hollow type, preferably buildings, the hollows of the wall constituting air spaces, 15 acting to keep out the cold.

Another purpose is to provide a mold for erecting such structures as will not necessitate lathing on the interior, as any suitable coating may be applied, direct to the interior 20 surface of the concrete or cement.

Still another purpose consists in the provision of a mold including auxiliary mold parts for forming the hollows or air spaces in the wall, said spaces extending vertically, 25 the auxiliary mold parts being so arranged and constructed as to form intermediate concrete walls between the spaces, and which intermediate walls connect with the exterior and interior parts of the wall. Furthermore, 30 more the auxiliary mold parts are capable of being easily removed, as the wall is constructed in a perpendicular direction, and adjusted to a higher position.

A further purpose is the provision of timbers interconnected in super-imposed positions on the exterior, to hold the mold plates in place, it being possible to remove the lower timbers and raise them to higher positions, until the wall is completed to the 40 desired height.

A still further purpose is the provision of means for supporting the mold timbers on the upper edge of the concrete or cement wall, as the wall is constructed.

45 It is to be understood that the particulars herein given are in no way limitative and that while still keeping within the scope of the invention, any desired modifications of detail and desired proportions may be made 50 in the apparatus according to circumstances.

The invention comprises further features and combination of parts, as will be herein-after set forth, shown in the drawings and claimed.

55 In the drawings:

Figure 1 is a sectional plan view, showing

the construction and arrangement of the mold, illustrating the concrete, cement or other plastic material as having been deposited therein for forming the wall of a 60 building structure.

Figure 2 is an enlarged detail sectional plan view of a portion of the wall and the mold, showing the wedges or spreaders as having been withdrawn from holding positions, whereby the interior mold plates for forming the air spaces may be removed.

Figure 3 is a vertical sectional view on line 3—3 of Figure 2, showing the construction of the wall and mold, showing the superimposed interconnected timbers, for holding the exterior mold plates.

Figure 4 is a detail perspective view of one of the plates for forming the hollows or chambers of the wall.

Figure 5 is a detail perspective view of the timber section 12.

Figure 6 is a detail perspective view of the spreaders.

Referring to the drawings, 1 and 2 designate the interior and exterior mold plates, which may be any suitable proportions, according to the size of wall or building to be constructed. These plates are adapted to be arranged in parallelism, to form the 80 mold walls, and 3 and 4 denote the mold plates for forming the air spaces in the concrete wall 5. These plates 3 and 4 adjacent their vertical longitudinal edges on their inner surfaces have beveled ribs 6. In 90 order to force the mold plates 3 and 4 in position and hold them equally spaced, spreading devices 7 are employed. Each spreading device comprises rods 8 having their adjacent ends threaded, and their outer 95 ends connected to wedges or spreaders 9, which are V-shaped in cross section and are adapted to engage the beveled ribs 6. Turn buckles 10 are engaged with the adjacent threaded ends of the rods 8, for moving 100 them from or toward each other, so as to force the wedges or spreaders between the beveled ribs 6, to force the plates 3 and 4 in position.

The exterior mold plates 1 and 2 are held 105 in place by timber sections 11, 13 and 14. These sections are slightly tapered vertically, as shown, in fact the outer surface of each section inclines toward the inner surface of each section at the upper end. The 110 lower end of each section is provided with a right angle cut away portion or recess 15,

which is of a shape or contour to receive and engage the upper end of the adjacent section. Where the sections of the timbers 11 interconnect in this manner, suitable bolts 5 or screws 16 are employed, to hold the sections aligned.

The upper sections 14 (which may act as the lower sections, when the sections 12 and 13 are arranged above the section 14) have 10 extending therethrough rods or bolts 17, the nuts 18 of which are adjustable on the rods, to hold the timbers in place, and to adjust them relatively spaced, for the purpose of holding the mold plates in position. 15 As the concrete wall increases in height, it is necessary to remove the lower succeeding timbers, and place them at the top, and furthermore it is necessary to support the timbers on the wall. In order to support the 20 timbers, props, such as rods 19, rest upon the upper edge of the unfinished wall, and are provided with forks 20, which straddle the rods 17. Obviously the timbers may be held in position, as the wall increases in 25 height. As the wall is constructed suitable tie or binding rods 21 and 22 are arranged vertically and transversely in the outer portions of the wall of the structure, for the purpose of reinforcing the concrete or cement. 30 Any form of reinforcing rods may be employed, tubular, solid or spiral rods may be embedded in the concrete or cement. Also embedded in the transverse connecting wall sections 23 are transversely disposed 35 reinforcing members 24. The inner portion of the wall of the structure, adjacent the corners thereof, and adjacent where the intermediate transverse wall parts are formed, vertical reinforcing rods 25 are used, which 40 are connected to the horizontal and vertical reinforcing rods of the outer portion of the wall, by means of the transverse reinforcing rods 24.

When the timbers are placed to hold the 45 exterior and interior mold plates in position, the heads 18 are adjusted upon the rods 17, and then the transverse timbers 26 are disposed between the upper ends of the timbers 14, in fact between the uppermost 50 sections thereof, there being rods 27 or bolts passing through the ends of the upper sections, through the timbers 26 and have wing nuts or heads 28 to bind the parts in position. It will be noted that by this construction the timbers 11 may be held equally 55 spaced.

When the sections of the timbers 11 are arranged in position, the recess or cut away portion 15 of each section receives the upper 60 end of the adjacent section, it being possible to remove the bolts or screws 16 of the lower sections, whereby the lower sections may be placed in engagement with the upper sections 14, and vice versa as the wall increases 65 in height. Suitable thumb screws 29 are

carried by the lower ends of the sections 12, to be adjusted, for engagement with the lowermost mold plates or boards, thereby preventing the lowermost mold plates or boards 30 from dropping downwardly out 70 of position.

Suitable additional mold plates as indicated at 31 may be used for forming the window openings 32, for the reception of the sashes (not shown), and without using 75 wood window frames. The hollow spaces of the wall constitute means to receive the sash weights, hence it is possible to form a wall structure having window openings, without the necessity of wood frames (not shown). 80 Mold sections, similar to those previously described may be used for forming the interior separating walls between the rooms, and in such a manner as to provide door openings, such as indicated at 33. These door 85 openings 33 have their jambs provided with bolts 34 embedded in the concrete, to hold wood blockings 35, for the reception of the trimmings 36.

A building wall of this character serves to 90 eliminate rats and mice and other pests, from inhabiting living houses, apartments and the like. Furthermore the air spaces formed within the walls will prevent the walls from sweating on the interior. Furthermore the exterior of the wall may be stucco, but may be otherwise given a decorative effect, as may be desired, the top of the building, or above the windows and door, or any other place. The use of window 95 frames may be eliminated, the walls may be made whatever thickness desired, it being possible to use the same structure of mold throughout the entire wall structure.

The exterior mold plates 2 may have different designs or impression surfaces, so that in constructing the wall, the exterior face of the wall may be decorated at the same time with the construction of the wall. In constructing the door opening 33, suitable iron bolts 34 may be anchored or otherwise fastened in the wall, and to which the wood pieces 35 are fastened. These pieces hold and support the door timber or frame 36. The thumb screws 29 are swivelled in 110 plates 29^a (which bear against the mold plates), and when the thumb screws are rotated or tightened, the plates bear against the lower mold plates and hold them in place, namely from slipping down.

The invention having been set forth, what is claimed as being useful is:

1. In a mold for constructing building walls, opposed mold boards or plates spaced according to the desired thickness of wall to 115 be built up, tapered timber sections disposed against the outer faces of said plates and arranged vertically, the sections on each side being in alignment, the inner face of the lower end of each section being cut away to 120

130

receive and engage the upper end of an adjacent section, means for fastening the sections together where they connect, a rod connecting the uppermost sections at a point 5 above said plates and having abutment means on its ends, and means between the extreme upper ends of the upper sections for spreading said upper ends and causing the lower ends of the lowermost sections to bind 10 against the plates.

2. In a mold for constructing building walls, opposed mold plates, to be spaced according to the thickness of wall to be constructed, interconnected timber sections arranged vertically adjacent the exterior surfaces of said plates, means passing through and connecting the uppermost timber sections at a point above the plates and provided with abutment devices adjacent the exterior surfaces of the timber sections, spacing devices arranged between and connecting the extreme upper ends of the timber sections, and hold the timber sections spaced according to the thickness of the wall, said 25 abutment devices being adjustable to draw the lower portions of the timber sections adjacent to and in contact with said plates.

3. In a mold for constructing building walls, opposed mold plates, to be spaced according to the thickness of wall to be constructed, interconnected timber sections arranged vertically adjacent the exterior surfaces of said plates, means passing through and connecting the uppermost timber sections at a point above the plates and provided with abutment devices adjacent the exterior surfaces of the timber sections, spacing devices arranged between and connecting the extreme upper ends of the timber sections, and hold the timber sections spaced according to the thickness of the wall, said 30 abutment devices being adjustable to draw the lower portions of the timber sections adjacent to and in contact with said plates, props engaging the means which passes through and connects the timber sections, to support the timber sections in position, and means connected to and carried by the lower ends of the timber sections for holding the plates in position. 35

In testimony whereof I hereunto affix my signature.

FRANK FLYNN.
